UNITED STATES PATENT OFFICE.

EVAN R. LEWIS AND LOUIS SALZINGER, OF WILKES-BARRE, PENNSYLVANIA.

CHIMNEY-MOTOR.

1,140,990.

Specification of Letters Patent.

Patented May 25, 1915.

Application filed July 9, 1914. Serial No. 850,010.

To all whom it may concern:

Be it known that we, EVAN R. LEWIS and LOUIS SALZINGER, citizens of the United States of America, residing at Wilkes-Barre, in the county of Luzerne and State of Pennsylvania, have invented certain new and useful Improvements in Chimney-Motors, of which the following is a specification.

This invention relates to improvements in chimney motors and an object of the invention is to concentrate the draft and to deflect the concentrated draft against a fan in such a way as to derive maximum power from the draft.

A further object of the invention is to provide a unit which may be applied to any chimney or draft creating means.

A still further object of the invention is to provide a support for a fan which carries means for directing the draft substantially at right angles to the plane of rotation of the fan.

With these and other objects in view, the invention consists in the arrangement, combination and construction of parts as will be hereinafter described and claimed.

In the accompanying drawings forming part of this invention, Figure 1 is a vertical section showing our invention as applied to the chimney; Fig. 2 is an enlarged fragmentary vertical section through the fan and draft directing devices as is shown in Fig. 1; Fig. 3 is an end elevation of the device for concentrating the draft; Fig. 4 shows a fragmentary view of a modified form of device for concentrating the draft.

The general aim of the present invention is to provide a substantially cylindrical housing closed on one end with a head or plate which is provided with either a plurality of funnels or cup-shaped depressions which communicate with tubes substantially parallel with the axis of a fan mounted directly behind the plate or head, a suitable pulley or other similar device being provided for driving machinery when the fan rotates.

Referring to the drawings, 1 shows an ordinary draft creating device as used with the usual power plants, etc. and for the sake of the present invention is shown as provided with a port 2 in communication with a cylindrical housing 3 which may be secured to the port 2 in any suitable manner as by a band 4. Provided within the cylindri-

cal housing are braces 5 in which is journaled a shaft 6, although one of these braces 5 will suffice as will appear hereinafter. Mounted upon the shaft 6 is a fan 7 of any suitable design having the blades set at any pitch and being of whatever special design may be found most expedient. This fan 7 is rigid with the shaft 6 and when the same rotates causes a pulley 8 to rotate with the shaft. We have not shown any particular mechanism to be operated by the fan, but it is to be understood that any machinery light enough to be operated by the fan can be connected thereto by means of the pulley 8.

As shown in Figs. 1 and 2, one end of the cylindrical housing 3 is reduced as at 9 to receive a flange 10 of a plate or head 11, the said plate being held to the cylindrical housing by means of bolts or rivets 12. This head or plate 11 forms an important part of the invention and in the preferred form as shown in Figs. 2 and 3, is provided with a plurality of cup-shaped depressions 13 80 from which extend tubes 14. While we have shown five of these cups and tubes in the drawing, yet more or less can be used as is found expedient and we do not wish to be limited to the particular position of the tube with respect to the blades of the fan. The tubes are preferably arranged concentrically with respect to the shaft so as to provide a plurality of jets of air of uniform strength which impinge upon the blades of 90 the fan. Again, it may be stated that this particular arrangement of the tubes 14 need not necessarily be followed to derive the benefits of the present invention. If desired, the position of the fan 7 with respect to the 95 head 11 may be made adjustable by means of a screw 15, the object of this adjustability being to enable the greatest amount of power to be derived from the fan by changing the position of the fan with respect to the tubes. 100 In order that this adjustability may be effected, the shaft is provided with a key-way 16 which receives a key 17 causing the shaft and fan to rotate in unison.

A modified form of draft concentrator is 105 shown in Fig. 4 where a head 19 is provided with a plurality of perforations 20 through which extend spouts 21 of funnels 22, the bowl of the funnel being spherical. These funnels extend beyond the outer face of the 110 plate 19 and may be used instead of the cup-shaped depressions 13. In order that the

draft operating the fan may be controlled, there is a damper 50 in the port 2.

It will be observed from the drawing that the tubes are substantially parallel to the shaft and that the jets of air issuing from the tubes strike the fan blades in a direction substantially perpendicular to the plane of rotation of the fan. It will further be noted that the air is concentrated at a few points 5 on the fan and by adjusting the position of the fan or by varying the position and number of the tubes, it will be possible to direct the jets against the fan at the most advantageous points. In order to insure smooth 10 running of the fan, and also to prevent the possibility of having the fan stop so that the jets issue between the blades, the number of tubes and the number of blades in the fan will preferably differ in number, in the 15 drawing, the fan is shown as provided with four blades, while five tubes are illustrated. As heretofore intimated, one of the supports 5 may be sufficient, in which case the plate 11 will form the other bearing for the shaft 6, 20 this bearing being desirable in view of the fact that the strain upon the shaft at the pulley 8 is spaced considerably from the supports 5 and also in view of the fact that it is not desirable to have any more obstruction placed in the path of the incoming air 25 than is absolutely necessary. In order to mount the device there have been shown in the drawing supports 18.

What we claim is:

- 35 1. A chimney motor comprising a substantially cylindrical housing, a fan rotatably mounted therein, a head for the cylindrical housing, and a plurality of tubes connecting with the outer air and extending toward the fan in a direction substantially parallel to the axis of the housing.
- 40 2. A chimney motor comprising a cylin-

drical housing opening at one end into the chimney, a head closing the other end of the housing, a shaft mounted in the housing, a 45 fan carried by the shaft and adapted to rotate in a plane substantially perpendicular to the axis of the housing and tubes communicating with the outer air and extending inwardly toward the fan in a direction substantially parallel to the shaft.

3. A chimney motor comprising a housing substantially cylindrical and opening at one end to the chimney, a head covering the other end of the cylindrical housing and provided on the outer face thereof with cup-like depressions, tubes communicating with the cup-like depressions and extending inwardly from the head substantially parallel to the axis of the housing and a fan rotatably mounted within the housing in proximity to said tubes and rotating in a plane substantially perpendicular to the axis of the housing.

4. A chimney motor comprising a substantially cylindrical housing opening at one end to the chimney, a head secured to the other end of the housing, a shaft extending parallel to and within the housing, means secured to the interior of the housing adapted to support one end of the shaft, the other end of the shaft passing through and being supported by said head, a fan carried by said shaft and tubes extending from the head toward the fan in a direction substantially parallel to the shaft, said tubes being in communication with the outer air.

In testimony whereof we affix our signatures in presence of two witnesses.

EVAN R. LEWIS.
LOUIS SALZINGER.
